UNITED STATES PATENT OFFICE

JOHN B. VAN DOREN, OF SOUTH BRAINTREE, MASSACHUSETTS

SOUND-MAKING DEVICE

Application filed January 20, 1930. Serial No. 422,024.

This invention relates to improvements in sound-making devices and the principal object of the invention is to provide a sound-making device of simple construction adapted to be actuated to produce a loud and substantially continuous sound.

A further object of the invention is to provide a sound-making device comprising a sonorous member and a plurality of hammers adapted to impinge upon the sonorous member at separated points and thereby to modify the normal vibration of the sonorous member to produce a jingle.

Another object of the invention is to provide a sound-making device having a flanged sonorous member provided with a handle having an extension overlying the flange of said sonorous member having a guideway or guideways for a hammer or hammers located within flanged portions of said sonorous member and having hammers slidably mounted in said hammer-supporting member operable upon oscillation of the device to impinge upon the flanges of said sonorous member.

25 A further object of the invention is to provide a sound-making device of the character specified of rigid construction which cannot be readily injured or broken.

Another object of the invention is to provide a sound-making device having a plurality of flanged sonorous members preferably reversely arranged and supported upon a handle with handle members extending over the respective flanged portions of the sonorous members and having hammer-supporting members located within the flanges of said sonorous members provided with guideways for a plurality of hammers, and hammers slidably mounted in said guideways to impinge upon opposite flanged portions of the respective sonorous members when oscillated by the handle.

Another object of the invention is to provide simple and novel supporting members for the hammers.

Another object of the invention is to provide a device of the character specified in which the sonorous members and the handle members are made of suitable metal with the

parts thereof welded together to provide an integral structure.

Another object of the invention is to provide a sound-making device of the character specified having a plurality of sonorous members which may be so constructed as to produce musical harmonic tones or discordant tones such as are often enjoyed in sound-making devices used in celebrations.

These and other objects and features of the invention will more fully appear from the following description and the accompanying drawings and will be particularly pointed out in the claims.

Preferred embodiments of the invention are illustrated in the accompanying drawings, in which,

Fig. 1 is a plan view of preferred forms of a sound-making device;

Fig. 2 is a longitudinal central sectional view on line 2—2 Fig. 1 showing a plurality of sonorous members;

Fig. 3 is a longitudinal sectional view of a similar device having a single sonorous member;

Fig. 4 is a detail view in perspective of the form of hammer-supporting and guiding device illustrated in Fig. 2; and,

Fig. 5 is a perspective view of the form of hammer-supporting and guiding devices illustrated in Fig. 4.

The sound-making device may comprise either one or two sonorous members 1, desirably of circular form having a peripheral flange 2 desirably extending at right angles to the plane of the circular portion 1 thereof. The sonorous member desirably is provided with a central offset portion 3 to which a handle member may be attached in any suitable manner, but preferably by welding.

In the construction illustrated in Fig. 2 the offset portions 3 of two reversely arranged sonorous members are secured, preferably by welding, to a central handle member 4. A looped handle member 5, which may be of half-round stock, is so bent as to provide sections 6 and 7 which contact with and embrace the central handle member 4 and are secured to it by welding, such as spot welds 8 located at suitable intervals. The sections 6 and 7

of the handle member are provided respectively with offset portions 9 and 10 merging into extensions 11 and 12 which preferably lie in parallelism with the planes of the circular body portions 1 of the respective sonorous members. Hammer-supporting members, which are secured to the respective extensions 11 and 12, are provided with guideways for the hammers located within the flanges 2 of the sonorous members.

In the particular construction illustrated in Fig. 2 the hammer-supporting members are identical in form and each comprises a plate 13, as more fully illustrated in Fig. 4, having a central offset portion or boss 14 which is secured preferably by welding to the extensions 11, 12, of the handle member. The plate 13 is provided with cylindrical flanged edges 15 lying in parallelism and hammers 16 are slidably mounted in the guideways formed by the cylindrical flanges. The hammers 16 are adapted upon oscillation of the device by its handle to impinge alternately upon opposite portions of the flange of said sonorous device and when the hammer is moved in either direction they strike upon the flange at separated points, thereby modifying the normal vibration of the sonorous member, which would be caused by the action of a single hammer, to produce a jingle.

The sonorous members 1 may be conveniently made of stamped or drawn metal of a resonant character and said sonorous members can be tuned to produce the same tone, harmonic tones, or discordant tones as may be desired. These sonorous members may be of the same size, or one can be made smaller than the other as illustrated by dotted lines in Figs. 1 and 2. By proper construction and tuning, therefore, one or several of such devices can be used to produce a harmony or even to play jingle tunes when used by several operators, or the device may be so constructed as to produce discordant tones and thereby consist purely in a sound-making device.

The construction illustrated in Fig. 3 shows a sound-making device comprising a single sonorous member. In this construction the handle preferably comprises a single metallic handle member of half-round stock having a straight section 17 which is secured, preferably by welding, to the offset portion or boss 3, a loop 18 and a straight section 19 which engages the straight section 17 and is secured thereto by spot welds 20. The section 19 is provided with an offset 21 and an extension 22 which preferably lies in parallelism with the section 17 and overlies and is separated from the flange 2 of the sonorous member. The hammer-supporting member in this construction is of a simple design and comprises a plate 23 having a central offset portion or boss 24, which is secured to the extension 22 preferably by welding, and downwardly flanged opposite edge portions 25 and 26. The flanges

25 and 26 are provided with aligned apertures 27 forming guides for the hammers 28. In this construction, as in that previously described, the hammer-supporting member is so arranged that the guideways for the hammers lie within the flange of the sonorous member.

In the operation of either of these devices the oscillation of the device by the handle causes a reciprocation of the hammers in such a manner that the hammers will strike alternately upon opposite flanged portions of the sonorous member or members. Obviously, a single hammer, or a plurality of hammers may be employed.

In the preferred constructions illustrated herein each sonorous member is of circular form having a continuous peripheral flange, but it will be understood that the sonorous members may be of rectangular form with the ends or sides thereof flanged, or may be of any desired form. The central portions of the sonorous members may, instead of being flat, be crowned, or of any desired contour, and other means obviously may be employed for supporting the hammer or hammers in such a manner as to cause the same to impinge upon the sonorous members.

It will, therefore, be understood that the embodiments of the invention shown and described herein are of an illustrative character and are not restrictive of the scope and meaning of the following claims.

Having thus described the invention, what is claimed as new, and desired to be secured by Letters Patent, is:

1. A sound-making device comprising a sonorous member, a hammer, means slidably supporting said hammer to permit the ends thereof to impinge alternately upon opposite portions of said sonorous member, and means for causing relative movement between said hammer and said sonorous member.

2. A sound-making device comprising a sonorous member, a supporting member therefor, a plurality of independently movable hammers reciprocably mounted on said supporting member to impinge upon different portions of said sonorous member, and means for causing relative movement between said hammers and said supporting member operable to cause the vibration imparted to said sonorous member by the impact of the respective hammers to modify the normal vibration of said sonorous member and thereby produce a jingle.

3. A sound-making device comprising a flanged sonorous member, a hammer-supporting member having oppositely disposed guides located within flanged portions of said sonorous member, a hammer slidably mounted upon said guides to impinge upon opposite flanged portions of said sonorous member, and means for causing relative movement between said hammer and said sonorous member.

4. A sound-making device comprising a flanged sonorous member having a handle connected thereto, a hammer-supporting member having a plurality of oppositely disposed guides located within oppositely disposed flanged portions of said sonorous member, hammers mounted in said guides to impinge upon opposite flanged portions of said sonorous member whereby upon oscillation of said sonorous member the impacts of the respective hammers will modify the normal vibration of the sonorous member and thereby produce a jingle. 10
5. A sound-making device comprising a flanged sonorous member having a handle connected to the central portion thereof, a hammer-supporting member located within oppositely disposed flanged portions of said sonorous member having oppositely flanged edges provided with hammer guideways, hammers reciprocably mounted in said guideways to impinge alternately upon opposite flanged portions of said sonorous member. 15
6. A sound-making device comprising a flanged sonorous member having a central offset portion, a handle member connected to said offset portion, a complementary handle member having an extension overlying the opposite side of said sonorous member, a hammer-supporting member on said extension and having a guideway located within oppositely disposed flanged portions of said sonorous member, and a hammer slidably mounted in said guideway. 20
7. A sound-making device comprising a circular sonorous member having a peripheral flange, a handle connected to said member, a hammer-supporting member mounted on said handle having a plurality of guideways located within said flange, and hammers reciprocably mounted in said guideways operable upon oscillation of said sonorous member to impinge alternately upon opposite portions of said flange. 25
8. A sound-making device comprising a flanged sonorous member, a handle secured thereto having an extension overlying the opposite side of said sonorous member, a hammer-supporting member secured to said extension having cylindrically flanged edges located within the flange of said sonorous member, and hammers slidably mounted in said cylindrically flanged edges. 30
9. A sound-making device comprising a flanged metallic sonorous member having a central offset portion, a metallic handle member having an end welded to said offset portion and provided with an extension overlying the opposite face of said sonorous member, a hammer-supporting member welded to said extension and provided with oppositely flanged edges having guideways for a plurality of hammers, and hammers reciprocably mounted in the respective guideways. 35
10. A sound-making device comprising a handle having a plurality of flanged sonorous members mounted thereon, hammer-supporting guides located within the respective flanged portions of said sonorous members, hammers slidably mounted in said hammer-supporting guides, and means for causing relative movement between said hammers and said sonorous members. 40
11. A sound-making device comprising two reversely arranged flanged sonorous members, a handle comprising a central member connected to the central portions of both of said members and a looped handle member embracing said central member having offset portions extending over the respective flanged portions of said sonorous members, hammer-supporting members connected to the respective ends of said looped handle member and having guideways located within the flanges of the respective sonorous members, and hammers slidably mounted in said guideways. 45
12. A sound-making device comprising two reversely arranged, circular, flanged, metallic sonorous members having offset central portions, a handle comprising a central member welded to the central offset portions of both of said sonorous members, and a looped handle member embracing said central member and welded thereto and having offset end portions extending over the flanges of the respective sonorous members, hammer-supporting members welded to the respective extensions of the looped handle member and located within the flanges of said sonorous members, and a plurality of hammers slidably mounted in each of said hammer-supporting means. 50
- In testimony whereof, I have signed my name to this specification. 55
